UNITED STATES PATENT OFFICE.

JAMES W. McCURLEY, OF CINCINNATI, OHIO, ASSIGNOR OF ONE-HALF TO LOUIS J. STOCKUM, OF CINCINNATI, OHIO.

WRENCH.

1,160,737.

Specification of Letters Patent. Patented Nov. 16, 1915.

Application filed February 19, 1915. Serial No. 9,401.

To all whom it may concern:

Be it known that I, JAMES W. McCURLEY, a citizen of the United States of America, and a resident of Cincinnati, in the county 5 of Hamilton and State of Ohio, have invented a certain new and useful Improvement in Wrenches, of which the following is a specification.

This invention relates to improvements in 10 wrenches adapted for use in connection with nuts, taps, piping, and the like and especially when various sizes of those devices are to be readily and quickly manipulated, and the object of the invention herein is to 15 provide a handled body-portion that has a fore serrated extension or jaw with a pair of removable side plates extending or projecting upwardly from said body-portion and having between their upwardly-extended 20 portions a pivotally-mounted rocker-bar whose smooth fore-end forms a companion jaw-member for the said serrated jaw-member and whose sloping rear end is engaged by a sloping toothed sliding plate or wedge 25 that is automatically advanced by and held under the control of a spiral spring, the latter being housed within the handle to the rear of said side-plates, whereby the pivotal jaw-member can be readily set and held in 30 position under said spring control in contact with the respective nuts or the like that are to be turned in either direction and not likely to slip away from the clamping-effect of the jaws but easily released from the jaws 35 without sticking, when required.

A very material object of the invention herein, and especially in connection with the said toothed, spring-controlled sliding plate or wedge is that the latter forms a positive 40 back-stop which is adapted to hold the upper pivotal-jaw from slipping and at the point where set, to suit various sizes of nuts or the like that are to be turned.

The details of the invention herein are 45 quite simple, easily understood and clearly pointed out in the following description of the accompanying drawings, in which,—

Figure 1 is a longitudinal side-elevation of my invention as it appears in use on a 50 nut that is clamped or held firmly in adjusting place between the jaw-members at the fore end of the wrench; Fig. 2, a longitudinal elevation of the wrench, showing it as it appears in its normal position when 55 out of use, but with the near one of the side-

plates removed, with the transverse pivot-bolt in section, with the plate fastening-rivets in section, and with the upper edge of the handle broken and in section lengthwise to clearly show the spring-control within 60 said handle for the plunger-stem portion of the toothed wedge; Fig. 3, a vertical cross-section taken on the dotted-line *a*, *a*, of Fig. 2 looking forwardly along the wrench; and Fig. 4, a plan view taken along the upper 65 edge of the wrench in the position seen in Fig. 1 but omitting the nut that is shown between the jaws in said Fig. 1.

1 indicates a middle or main portion of 70 the longitudinal bar that has an integral fore jaw-extension 2 and an integral rear handle-extension 3, the lower edge of all three of these parts being on the same plane, but the upper edge of the said handle-extension is elevated somewhat above the upper 75 edge of the said main-portion 1 and is made hollow or bored throughout its length to form a chamber 4 whose rear end is fitted with a tightly-driven plug 5 and is adapted to accommodate the rear plunger-stem 6^a of 80 a sliding wedge or clamp-member 6 whose lower edge reciprocates along the upper edge of said main-portion 1 that lies in the same plane as the bottom of chamber 4, as seen in Fig. 2. The upper face of the jaw-extension 2 slopes downwardly and is toothed or serrated as shown at 7, and the fore end of the wedge or clamp-member 6 is also made sloping and toothed or serrated 85 as shown at 8.

Within the chamber 4 I insert a spiral 90 spring 9, as seen in Fig. 2, said spring acting expansively between the rear end of the plunger-stem 6^a and the rear-plug 5, the latter forming a back-stop for the spring 95 and enabling the ready boring of the chamber 4 in the manufacture of the device. In order to more readily adjust the tension of the spring 9 I prefer to make it in two 100 coils whose adjacent ends are adapted to interwind to suit the stiffness or tension desired. In assembling the device the spring 9 is inserted from the fore end of the chamber 4, and the plug 5 is driven tightly into place in the rear end of said chamber. The wedge or clamp-member 6 together with its integral stem 6^a is removably-mounted in place for use and automatically projected forward under the tension of said spring 9 so that the toothed fore edge 8 shall succeed 105 110

sively engage the rear, pointed end or sharp tail 10 of an upper or auxiliary jaw-member 11, the latter having at its fore end an upwardly-sloping, smooth-faced, jaw proper 5 12 that is adapted to co-act with the lower or main jaw-member 2 whose serrated surface 7 is adapted to firmly grip the nut or other object that is to be turned, the smooth surface of the upper pivotal jaw 12 being 10 adapted to readily release said nut or other object when desired and not stick at that particular releasing moment when the clamping-effect of the jaws should be easily removed from said nut so as to make ready for 15 the next clamping of the nut in continuing the turning thereof for use or the reverse.

The upper jaw-member is freely and pivotally mounted on a transverse bolt 13 between a pair of side-plates 14 and 15, the 20 said side-plates being firmly secured in place on the body-portion 1 of the wrench by means of countersunk rivets 16, and a removable nut 17 is used on the pivot-bolt 13 so that the latter can be removed when desired in placing and displacing said upper jaw-member from between the side-plates 14 and 15. The rear ends of the side-plates 14 and 15 are made shallower than their 25 fore portions, as shown at 18 in Fig. 1 and 30 bear against shoulders 18^a at the fore end of handle 3 as in Fig. 2, and with their upper edges on the same plane as the upper edge of said handle whereby the operator can more readily take hold of the upper 35 portion of the wedge 6 between his thumb and fore-finger although the upper face of said wedge is somewhat serrated or knurled, as at 19, for the pressure of the thumb thereon in manipulating said wedge back- 40 wardly from toothed-engagement with the pointed rear end 10 of the upper jaw-member. In operating the wrench, the wedge 6 is drawn rearwardly against the pressure of spring 9 so that the tooth 10 of the upper 45 jaw-member may be brought into engagement with the proper tooth of series 8 to suit the space required between the jaw-faces 7 and 12 to accommodate the nut, tap or other object that is to be turned or affected by the use of the wrench, during 50

which time the spring 9 exerts its tension on the wedge 6 and holds it firmly against said tooth 10 so that the upper jaw-member cannot slip accidentally from the nut to be turned. The upper jaw-member can be 55 readily released from the nut by drawing the wedge backwardly by means of the thumb on the knurled-surface 19 so that it can be pivoted on the bolt 13 between the side-plates 14 and 15 that are mounted just 60 free from contact with its opposite sides and not interfering with its regular movements. The said side-plates have no clamping effect on said upper jaw-member that would retard it in any way in use. 65

I claim:—

A wrench comprising a flat, plane or smooth main-member having a fore or main jaw-extension that has a serrated or toothed contacting-face and a rear plane or smooth 70 rear handle-extension that has in its upper edge a longitudinal chamber, a pair of independent flat plates secured to the opposite sides of the main-member intermediate the said fore jaw-extension and the rear handle-extension and projecting upwardly beyond its upper edge, an upper plane auxiliary jaw-member pivotally-supported between the upper extensions of said plates and having a sharp tail-end, a flat clamp-plate or wedge 75 having a toothed sloping fore-edge and a rear smooth integral plunger-stem that is adapted to slidingly-engage the longitudinal 80 smooth bore or chamber within the upper edge of the handle, and a longitudinal 85 spiral spring inserted within said chamber and adapted to act expansively on the rear smooth plunger-stem of the toothed clamp-member or wedge so that the teeth of the latter shall automatically engage the said 90 sharp tail-end of the pivotal jaw-member when in use on a nut or the like and the said clamp-member or wedge adapted for ready release from tight engagement with the pivotal jaw-member by a rear movement against 95 the tension of the spring.

JAMES W. McCURLEY.
